The Lowell Manufacturing Company,

The schedule referred to in these Letters Patent and making part of the same.
To all whom it may concern:

Be it known that I, Clemir J. Ney, of Lowell,
in the County of Middlesex, and State of Massachusetts, have invented

1. which has an irregular border. The corners 2. 3. 4. 5. when matched form a figure similar to A. and meeting on a similar ground.

The four groups of flowers and leaves 6. 7. 8. 9. lie between, and at equal distances from, the centre and corners.

Continuous branches of sprigs run between the groups 8. 7. 8. 9. and the centre and corners, and, by their intersections at the sides and ends of the design, surround the grounds on which rest small stars, halves of which are shown in the drawing.

The colors employed for the different portions of the design may be varied to suit the taste and wish of the manufacturer.

Claim
